UNITED STATES PATENT OFFICE.

CHARLES H. SHAW, OF BROOKLYN, NEW YORK, ASSIGNOR TO JOHN P. ADAMS, TRUSTEE, OF SAME PLACE.

NIGHT-CLOCK.

SPECIFICATION forming part of Letters Patent No. 339,220, dated April 6, 1886.

Application filed June 29, 1885. Serial No. 170,054. (No model.)

To all whom it may concern:

Be it known that I, CHARLES H. SHAW, of Brooklyn, in the county of Kings and State of New York, have invented a certain new and useful Improvement in Clocks, of which the following is a specification.

The object of my improvement is to produce a simple, cheap, and neat clock, which will be convenient and effective for indicating time in a dark room.

In my clock I use a train of time-registering wheels, a platform rotated by the same once every twelve or twenty-four hours, a translucent globe or shade bearing opaque or semi-opaque figures or numbers carried by the platform, and a stationary hand or index.

In the accompanying drawings, Figure 1 is a sectional elevation of a clock embodying my improvement. Fig. 2 is a horizontal section 20 of the same, taken at the plane of the dotted line *x x*, Fig. 1.

Similar letters of reference designate corresponding parts in both figures.

A designates a train of wheels for registering time. This train may be of any approved type. It is arranged in a case, *B*, in such position that an arbor, *a*, which makes a rotation once every twelve hours, is vertical. The case *B* is shown as circular and tapering 30 upwardly.

C designates a platform, which is supported on the arbor *a*. It may be only friction-tight, or the said arbor may have only a friction-tight connection with a part from which it 35 derives motion. This platform of course makes a complete rotation in every twelve hours.

On the platform *C* an illuminating device is

arranged. It consists, as here shown, of a candle, *D*, fitted in a socket or candlestick, *E*. 40 The outer edge of the platform *C* is upturned to form a rim, *c*. A globe or shade, *G*, made of translucent material, preferably opal glass, is fitted upon the platform *C*, inside its rim *c*. It is carried by the platform, and hence makes 45 a complete rotation once every twelve hours. As shown, it tapers upwardly; but it may be made of other shape. On it are delineated numbers indicative of the different hours of the day, running from one to twelve. The 50 globe is illuminated by the light inside it. The numbers will be delineated in opaque or semi-opaque material; hence they will be conspicuous and easily discerned.

On the case *B* of the train of wheels *A*, a 55 hand, *J*, is arranged. It is stationary, and extends upward into the range of the numbers upon the globe. The position of the numbers on the globe with relation to the hand indicates the time.

What I claim as my invention, and desire to 60 secure by Letters Patent, is—

In a clock, the combination of a train of time-registering wheels arranged in such position that the hour shaft or arbor is vertical, 55 a platform carried by said hour shaft or arbor, a translucent globe or shade arranged on the platform and marked with numbers in opaque or semi-opaque material, an illuminating device inside the globe or shade, and a 70 stationary hand, substantially as specified.

CHAS. H. SHAW.
